UNITED STATES PATENT OFFICE.

WILLIAM CANOVA, OF PATERSON, NEW JERSEY.

TENSION DEVICE.

1,414,175.

Specification of Letters Patent. Patented Apr. 25, 1922.

Application filed February 1, 1922. Serial No. 533,281.

To all whom it may concern:

Be it known that I, WILLIAM CANOVA, a citizen of the United States, residing at Paterson, in the county of Passaic and State of New Jersey, have invented certain new and useful Improvements in Tension Devices, of which the following is a specification.

Shuttle tension devices of the class in which a thread-controlling member moves pivotally back and forth to bring its thread guides into and out of alternating relation to a series of fixed thread guides in the shuttle have heretofore usually had these thread-controlling members made either of suitably bent wire or stamped out of sheet metal. The latter form is the more preferable for several reasons, among which is that it makes possible the use of separately formed guides and consequently the substitution of new guides for worn ones.

My present invention relates to the second class of such thread-controlling members, and it has for its object to form the body portion of the member and parts to constitute loops upstanding therefrom and serving either as, or to receive eyelets to form, guides all from a single blank of sheet metal.

30 In the accompanying drawing,

Fig. 1 is a side elevation of a fragment of a shuttle containing a tension means of the class specified having the improved pivoted thread-controlling member, the shuttle appearing partially in section;

Fig. 2 shows the blank from which said member is formed, and, in dotted outline, the piece of sheet metal out of which it is stamped;

40 Fig. 3 is an enlarged sectional view on the line 3—3 of Fig. 1, looking toward the left; and

Fig. 4 is a sectional view through one of the loops and an eyelet held thereby as shown in Fig. 1.

45 *a* designates the usual series of fixed thread guides in a shuttle *b*, *c* being the thread which extends through a guide *d* from the quill cavity *e* to the cavity *f* containing the tension means and then from said cavity *f* laterally of the shuttle in the usual way.

From a suitable blank *g* of sheet metal shown by the dotted outline in Figure 2 a blank is cut out. This blank consists of an elongated body portion *h* which is slender

throughout its length excepting at *i*, where it is widened, the portion *i* being nearer one end of said body portion than the other. The longer part *h'* extending from the part 60 *i* has at regular intervals long slender arms *j* projecting therefrom and at the other edge and in registry with said arms notches *k* formed therein. The part *h* projecting from said portion *i* has a hole *l* formed in 65 the extremity thereof.

Having formed this blank it is shaped as follows: The portion *i* is bent on a transverse axis into substantially cylindrical form to produce the bearing *m*, Fig. 1, leaving the longer part *h'* true to its original plane, and the shorter part *h* is bent downwardly so as to stand at more or less of an angle to the part *h'*. Each arm *j* is bent inwardly over and close to the part *h'*, as at 70 *j'* (Fig. 3); and then upwardly over, downwardly and inwardly to form a substantially circular loop *j*; and then has its free end portion bent outwardly and inwardly to form a hook or clip *j* which is adapted to 75 engage in the corresponding notch *k* of the part *h'*. The metal is tempered, preferably, so as to have a certain amount of elasticity, i. e., sufficient to return the hook *j* into the same.

The device thus formed is adapted to be pivoted on the usual pivoting pin *n* provided for the pivoted thread-controlling member of a shuttle tension device of the 90 class indicated, its portion *m* forming the bearing, and it is also adapted to have engaged with the arm formed by its part *h*, to wit, in the hole *l* of said part, the usual elastic device *o* for normally holding the 95 member in the position shown in Figure 1.

The naked loops *j* may form the thread guides of the member; or I may equip said member with a series of porcelain or metal eyelets *p* of well-known form which the 100 loops *j* peripherally embrace, these eyelets having peripheral grooves *p'* in which the loops engage. Where such eyelets or other removable guides are used they may be readily replaced when worn by springing 105 the hooks *j* out of the notches sufficiently to expand the loops *j* and release the eyelets.

Having thus fully described my invention, what I claim as new and desire to secure by Letters Patent is:

1. A thread-controlling member for a tension device of the class specified consisting

of an elongated piece of stiff material having a series of integral arms arranged one after another along the same and each extending from one side of the piece and being bent 5 into a loop upstanding from the piece and having its free end engaging and interlocked with the other side of the piece.

2. A thread-controlling member for a tension device of the class specified consisting of 10 an elongated piece of stiff material having a series of integral arms arranged one after another along the same and each extending from one side of the piece and being bent into a loop upstanding from the piece and 15 having its free end hook-shaped and receiving the other side of the piece.

3. A thread-controlling member for a tension device of the class specified consisting of an elongated piece of stiff material having 20 a series of integral arms arranged one after another along the same and each extending from one side of the piece and being bent into a loop upstanding from the piece and having its free end engaging the other side 25 of the piece, said other side having a notch to receive the free end of such arm.

4. A thread-controlling member for a tension device of the class specified consisting of an elongated piece of stiff material having a series of integral arms arranged one after 30 another along the same and each extending from one side only of the piece and being bent into a loop upstanding from the piece, in combination with an eyelet peripherally 35 embraced by said loop.

5. A thread-controlling member for a tension device of the class specified consisting of an elongated piece of stiff material having a series of integral arms arranged one after 40 another along the same and each extending from one side only of the piece and being bent into a loop upstanding from the piece.

6. A thread-controlling member for a tension device of the class described consisting of a sheet-metal blank having an elongated 45 body part and integral arms projecting laterally from one side of said body part, each arm of the blank being bent up and over the body part into the form of a thread-guiding loop.

In testimony whereof I affix my signature.
WILLIAM CANOVA.
